UNITED STATES PATENT OFFICE.

HOMER C. SNOOK, OF SOUTH ORANGE, NEW JERSEY, ASSIGNOR TO WESTERN ELECTRIC COMPANY, INCORPORATED, OF NEW YORK, N. Y., A CORPORATION OF NEW YORK.

VACUUM PUMP.

Application filed June 16, 1921. Serial No. 477,916.

To all whom it may concern:

Be it known that I, HOMER C. SNOOK, a citizen of the United States, residing at South Orange, in the county of Essex, State 5 of New Jersey, have invented certain new and useful Improvements in Vacuum Pumps, of which the following is a full, clear, concise, and exact description.

This invention relates to an auxiliary 10 pump adapted to cooperate with a roughing pump for exhausting to low pressures. It is particularly, although not exclusively, useful for the production of high vacua necessary in vacuum tubes of the pure 15 electron discharge type.

In the application of W. G. Houskeeper Serial No. 478,975, filed June 20, 1921, there is disclosed an auxiliary pump in which is employed a pumping medium having at 20 room temperatures a vapor pressure less than the pressure desired in pure electron discharge devices, whereby is avoided the use of the liquid air trap necessary in mercury vapor pumps. A metal such as lead, 25 bismuth, tin or the like is vaporized from a molten puddle of the metal, introduced into the pumping chamber in the form of a jet and caused to act mechanically upon gas admitted to the pumping chamber from 30 the vessel to be exhausted to expel the gas from the pumping chamber in the usual manner, after which the vapor is condensed and returned to the puddle to be vaporized again.

The object of this invention is a simple 35 and effective pump for producing the jet of pumping vapor and returning the condensed pumping medium to its sources.

An embodiment of the invention com- 40 prises a metallic casing containing a puddle of molten metal maintained at a temperature slightly above the melting point of the metal, a portion of which puddle or another puddle fed therefrom is maintained at a 45 temperature for which the vapor pressure of the metal is in excess of the pressure obtainable by a roughing pump to cause the emanation therefrom of a vapor jet useful as the pumping medium. A shield is pro- 50 vided to lead the condensed metal back into the lower temperature portion of said puddle or into the lower temperature puddle.

This invention will be better understood 55 by having reference to the following speci- fication and accompanying drawing wherein

Fig. 1 is an elevation showing the relation between the roughing pump, the auxiliary pump and the receptacles to be exhausted and Fig. 2 is a cross section of the auxiliary pump itself.

In Fig. 1, 1 designates a roughing pump capable of exhausting to a pressure of 10⁻³ mm. of mercury, 2 is the auxiliary pump, and 3 are the receptacles to be exhausted.

In Fig. 2, 4 is a cylinder of the metal inert to the metal to be used as the pumping medium and is provided with a re-entrant tubular portion 5 near the inner end of which is provided a partition 6 forming the 70 bottom of a cup 7. At the upper end of the cylinder 4 is provided an integral sleeve 8 spaced from the outer wall of the cylinder to form an annular container 9. The upper end of the sleeve 8 is screw threaded internally and a cap 10 is screwed into the sleeve. Arranged coaxially of the cap is the integral tubular member 11 which extends inwardly a short distance and which connects the roughing pump 1 with the auxiliary 75 pump. A second tubular member 12 leads off from the cap at right angles to the member 11 and is joined to a glass tube 13, leading to the containers 3, according to the method disclosed in the patent to W. G. 80 Houskeeper 1,294,466. Threaded into the upper end of the cup 7 is an expanding nozzle 14. Surrounding the nozzle 14 but out of contact therewith is a conical shield 85 90 15, the lower end of which extends over and rests upon the upper edge of the cylinder 4. The lower portion of the cup 7 and the annular chamber 9 between the cylinder 4 and the sleeve 8 are connected by means of a tube 16 of such small diameter 95 that the thermal conductivity of the metal therein is very slight.

Arranged in the upper end of the re-entrant portion 5 is a heating unit which, in this instance, comprises a mass 17 of 100 granular carbon held in place by means of a porcelain insulator 18 through which extends the carbon rod 19. The lower end of the carbon rod and the lower end of the cylinder 4 are electrically connected to opposite poles of a source of electrical energy 105 20.

An oven 21, having a cap 20^a, which encloses all of the auxiliary pump and a portion of the member 11, is provided with 110

an electrical heating unit 22 connected to the source of electrical energy 20. The heating unit 22 may be extended to the top of the oven, if desired.

5 In the operation of this device a metal, such as lead, tin, bismuth or the like having temperatures near its melting point, a vapor pressure less than the gas pressure within a vacuum tube of the pure electron discharge type, is placed in the cup 7 and in the annular chamber 9 between the cylinder 4 and the sleeve 8. A seal 23 of the same metal is provided between the cap 10 and the sleeve 8. The metal in the annular puddle 10 and the walls of the pump are maintained at a temperature slightly above the melting point of the metal by means of the heating unit 22. The metal in the cup 7 15 is heated by means of heat generated in the mass of granular carbon to a temperature at which its vapor pressure is approximately 1 mm. of mercury, whereby is caused the emanation therefrom of a jet of vapor which passes into the tubular member 11 through the nozzle 14. This vapor acts 20 mechanically upon the gas admitted to the auxiliary pump from the containers 3 and drives it toward the roughing pump 1. The vapor is condensed on the inner wall of the 25 tubular member 11 in a liquid condition because this member is at a temperature slightly above the melting point of the metal, flows down the tube, drops on to the shield 14 and is returned to the annular or low temperature 30 puddles. As the metal is vaporized from the inner puddle, metal flows thereinto from the annular puddle through tube 16 under hydrostatic pressure. The operation 35 is thus made continuous. Because of the fact that at temperatures near its melting 40 point the pumping medium has a vapor pressure less than the gas pressure with a vacuum tube of the pure electron discharge type there is no tendency for the vapor to 45 dissipate into the vessel to be exhausted.

The transfer of heat from the inner puddle to the outer puddle through the tube 16 is prevented because of its small thermal conductivity and the relatively small thermal 50 conductivity of the column of molten metal within the tube 16. The high vacuum between the cup 7 and the inner wall of the chamber 9 prevents the transfer of heat from the high temperature puddle to the low 55 temperature puddle. The puddle of metal in the chamber 9 is thus kept at the temperature for which its vapor pressure is less than that desired in the vessel to be evacuated. The expanding nozzle 14 gives to the 60 vapor jet a substantially parallel flow so that the jet is effective to drive the gas a considerable distance before condensing on the sides of the tube 11.

65 The thermal conduction from the high temperature nozzle 14 by the shield 15 is

made very slight by the use of a material of small specific thermal conductivity for constructing the shield 15; by making 15 of thin material; and by having small area of contact with 14.

70 What is claimed is:—

1. In a vacuum pump, a puddle of molten metal having two portions, one of which is maintained at a temperature substantially higher than the temperature of the other portion, means for heating each of said portions, means for introducing the gas from the vessel to be exhausted into the vapor stream emanating from the high temperature portion of the puddle, and means 75 80 for causing the metal condensed from the vapor stream to return to the low temperature portion of the puddle.

2. An auxiliary pump, adapted to cooperate with a roughing pump for exhausting to low pressures, comprising a chamber connected to the roughing pump and to the vessel to be exhausted, a material in said chamber capable of furnishing a supply of vapor, means for heating a portion of said material and the walls of said chamber, and means for heating the remaining portion of said material to a higher temperature whereby the vapor stream used for pumping will emanate from the last mentioned portion of 85 90 95 the vaporizable material.

3. In a vacuum pump, a chamber, a supply of material in said chamber capable of furnishing a pumping vapor, means for maintaining said supply of material and the walls of said chamber at a temperature slightly above the melting point of said material, a second supply of said material in communication with said first supply, and means for heating said second supply of material to a higher temperature whereby the vapor stream used for pumping will 100 105 emanate from said last named supply of material.

4. In a vacuum pump, a chamber, a supply of material in said chamber capable of furnishing a pumping vapor, means for maintaining said supply of material and the walls of said chamber at a temperature slightly above the melting point of said material, a second supply of said material in communication with said first supply, and means for heating said second supply of material to a higher temperature whereby the vapor stream used for pumping will 110 115 120 emanate from said last named supply of material, and means for causing the metal condensed from the vapor stream to return to the low temperature supply.

5. In a vacuum pump, a chamber, a supply of material in said chamber capable of furnishing a pumping vapor, means for maintaining a portion of said material and the walls of said chamber at a temperature slightly above the melting point of said ma-

- terial, a heating unit for maintaining the remaining portion at a temperature sufficiently high to produce a vapor stream therefrom.
5. In a vacuum pump, a chamber, a supply of material in said chamber capable of furnishing a pumping vapor, means for maintaining a portion of said material and the walls of said chamber at a temperature 10 slightly above the melting point of said material, a heating unit for maintaining the remaining portion at a temperature sufficiently high to cause the emanation of a vapor stream therefrom, and means for 15 causing the metal condensed from the vapor stream to return to the low temperature portion of the supply.
6. In a vacuum pump, a chamber, a supply of material in said chamber capable of 20 furnishing a pumping vapor, means for maintaining a portion of said material and the walls of said chamber at a temperature slightly above the melting point of said material, and an electrical heating unit in close 25 relation with the remaining portion for heating said material to cause the emanation therefrom of a jet of vapor.
7. In a pump, a chamber, a supply of material in said chamber capable of furnishing 30 a pumping vapor, means for maintaining a portion of said material and the walls of said chamber at a temperature slightly above the melting point of said material, an electrical resistance heating unit in close 35 relation with the remaining portion for heating said material to cause the emanation therefrom of a jet of vapor.
8. In a pump, a chamber, a supply of material in said chamber capable of furnishing 40 a pumping vapor, means for maintaining a portion of said material and the walls of said chamber at a temperature slightly above the melting point of said material, an electrical 45 resistance heating unit in close relation with the remaining portion for heating said material to cause the emanation therefrom of a jet of vapor.
9. In a pump, a chamber, a supply of material in said chamber capable of furnishing 50 a pumping vapor, a container therefor, means for maintaining a portion of said material and the walls of said chamber at a temperature slightly above the melting point of said material, a mass of granular carbon 55 in contact with a portion of the bottom of the container, and means for supplying current thereto.
10. In a pump, a plurality of containers 60 therein, a tubular connection between said containers, a mass of granular carbon in contact with the bottom of one container, and means for supplying current thereto.
11. In a pump, a plurality of containers, a heat insulating tubular connection between 65 said containers, a mass of granular carbon in contact with the bottom of one of said containers, and means for supplying current thereto.
12. In a pump, a chamber, a supply of material in said chamber capable of furnishing 70 the pumping vapor, electrical means for heating a portion of said material to cause the emanation therefrom of a vapor stream, electrical means for heating the remaining portion of said material and the 75 walls of said chamber, and a common source of electrical energy for both of said heating means.
13. In a pump, a metal cylinder having a re-entrant hollow portion, a container integral with said re-entrant portion, an annular container concentric with said first container, a cover for said cylinder, said cover having an opening therethrough, a tubular connection between said containers, and a heating element in said re-entrant portion. 80
14. In a pump, a metal cylinder having a re-entrant hollow portion, a container integral with said re-entrant portion, an annular container concentric with said first container, a heat insulating tubular connection between said containers, and a heating element in said re-entrant portion. 85
15. In a pump, a metal cylinder having a re-entrant hollow portion, a container integral with said re-entrant portion, a mass of granular carbon arranged at the inner end of said re-entrant portion, and electrical 90 means for passing current through said carbon mass.
16. In a pump, a metal cylinder having a re-entrant hollow portion, a container integral with said re-entrant portion, a mass of granular carbon arranged at the inner end of said re-entrant portion, an insulating block in said re-entrant portion, a carbon rod extending through said block into the granular carbon, and electrical connections 95 between said rod and said cylinder with a source of electrical energy. 100
17. In a vacuum pump, a metal cylinder having a re-entrant hollow portion, a container integral with said re-entrant portion, an annular container concentric with said first container, a nozzle carried by said inner container, a conical shield extending from said nozzle over the inner wall of said annular container, a tubular connection between said containers and means for heating material in said containers. 105
18. In a pump, a metal cylinder having a hollow re-entrant portion, a container integral with said re-entrant portion, and a heating element arranged within said re-entrant portion. 110
19. In a pump, a plurality of connected puddles of pumping medium, and means for heating said puddles to different temperatures, said puddles being thermally insulated from each other. 115
20. In a pump, a plurality of puddles of pumping medium, and means for heating each of said puddles to a different temperature. 120
21. In a pump, a plurality of puddles of pumping medium, and means to heat one of said puddles to the melting temperature of said medium and the other to higher temperature. 125

22. The method of operating a vapor pump which consists in maintaining in molten condition two puddles of pumping material having at temperatures near its melting point a vapor pressure less than the gas pressure within a vacuum tube of the pure electron discharge type, causing the emanation from one of said puddles of a vapor jet, utilizing said vapor jet to entrain gas from a vessel being exhausted, condensing said pumping medium to its liquid form, and causing it to flow into the other of said puddles.
23. The method of operating a vapor pump which consists in utilizing as a pumping medium a substance having at temperatures near its melting point a vapor pressure less than the gas pressure within a vacuum tube of the pure electron discharge type, maintaining a puddle of said substance at melting temperatures, heating another puddle to a higher temperature to cause the emanation therefrom of a vapor jet, utilizing said vapor jet to entrain gas from a vessel being exhausted, condensing said substance to liquid form and causing it to flow into the lower temperature puddle.
24. In an auxiliary pump, a pumping chamber, a plurality of puddles of pumping medium having at temperatures near its melting point a vapor pressure less than the gas pressure within a vacuum tube of the pure electron discharge type, means to heat one of said puddles to cause the emanation therefrom of a vapor jet, means to maintain said pumping chamber and said other puddle at the melting temperature of said metal, and means to lead the condensed medium into said low temperature puddle.
25. The method of operating a vacuum pump which comprises heating a puddle of pumping substance to its melting temperature heating another puddle of said substance to a higher temperature to cause the emanation therefrom of a vapor stream, utilizing said vapor stream to entrain gas from a vessel being exhausted, condensing said substance to liquid form and causing it to flow into said low temperature puddle.
26. The method of operating a vacuum pump which comprises heating two puddles of pumping substance to molten condition, causing the emanation of a vapor jet from one of said puddles, utilizing said vapor jet to entrain gas from a vessel being exhausted, and feeding said puddle from said other puddle.
27. The method of operating a vacuum pump which comprises heating a supply of pumping substance to molten condition, heating a small portion of said supply to a higher temperature to cause the emanation therefrom of a vapor stream, and utilizing said vapor stream to entrain gas from a vessel being exhausted.
28. The method of operating a vacuum pump which comprises heating a supply of pumping substance to molten condition, heating a small portion of said supply to a higher temperature to cause the emanation therefrom of a vapor stream, utilizing said vapor stream to entrain gas from a vessel being exhausted, condensing said substance to its liquid condition and returning it to the low temperature portion of said supply.
29. In a pump, a pumping passage, a conduit leading from the vessel to be evacuated to said pumping passage, a container enclosing said pumping passage, and means for heating said container.
30. In a pump, a pumping passage, a conduit leading from the vessel to be exhausted to said pumping passage, a receptacle for the pumping substance, an oven enclosing said parts, and a heater in the oven.

In witness whereof, I hereunto subscribe my name this 14th day of June A. D., 1921.

HOMER C. SNOOK.
